FAUCET RE-SEATING TOOL

Sidney J. Shames, 19 Agnes Circle, and Harold Shames,
5 Agnes Circle, both of Ardsley, N.Y.
Filed Apr. 10, 1961, Ser. No. 101,901
6 Claims. (Cl. 90—12.5)

This invention relates to a faucet re-seating tool.

Faucet re-seating tools have heretofore been known in a variety of types. In one such tool, after the valve stem of the faucet has been removed, the gland, or cap nut, of the faucet is reassembled on the stem of the tool for reconnection to the faucet body for the purpose of assisting in centering the tool to effect proper reseating of the valve seat. However, in such devices, the stem of the tool is generally smaller than the smallest interior dimension of the cap nut and, therefore, there is bound to be wobble in the tool and the tool does not reseat squarely.

In another such tool, a tapered self-threading cone is provided on the stem of the tool for threaded connection to the faucet bonnet. However, since the thread on the cone is always a helix, it can never align the tool perfectly square with the valve seat of the faucet. Another deficiency with this tool is that if the faucet bonnet is weak the force from the cone in attaching to the bonnet may seriously damage the faucet.

A further deficiency of both said tools is that in recent faucet constructions the bonnet is quite shallow and there is little vertical space between the bonnet and the faucet's valve seat. It has been observed that the aforementioned commercial tools cannot be used with such faucet constructions.

Thus, one object of this invention is to provide an improved faucet re-seating tool that avoids the deficiencies hereinabove noted and that connects to the interior of the faucet bonnet to thereby center and align the faucet seat cutter to cause the tool to re-seat squarely.

Another object of this invention is to provide a faucet re-seating tool wherein the stem of the tool is used both to effect connection of the tool to the faucet bonnet and to operate the valve seat cutter after the tool has been connected to the faucet bonnet.

Still another object of this invention is to provide a faucet re-seating tool with radial expandable means for selectively connecting the tool in true centered assembly to a faucet bonnet, and to thereby square-up the seat cutter with the valve seat that is to be cut.

A further object of this invention is to provide a faucet re-seating tool that is characterized by simplicity and effectiveness of operation and by economy of construction.

And a further object of this invention is to provide an improved cutter for use with a faucet re-seating tool.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawings, in which:

FIGURE 1 is a perspective view of the tool constructed in accordance with our invention;

FIGURE 2 is a perspective exploded view of the parts of the tool shown in FIGURE 1;

FIGURE 3 is a view partly in elevation and partly in vertical axial cross-section showing the tool in FIGURES 1 and 2 being connected to a faucet bonnet;

FIGURE 4 is a view similar to FIGURE 3 showing the tool of FIGURES 1 and 2 being used to re-seat the faucet's valve seat;

FIGURE 5 is a fragmentary view similar to a portion of FIGURE 4 showing use of the tool with a faucet having a smaller bonnet and valve seat than in the faucet

2

shown in FIGURES 3 and 4, and also showing further use of the improved cutter.

Referring now to the drawings, the faucet re-seating tool is generally indicated at 10, and the parts thereof are individually best seen in the exploded view of FIGURE 2. The parts of tool 10 includes an elongated, generally smooth-walled, cylindrical stem, or shaft, 12 whose upper end has a handle 14 connected thereto, and whose lower end has a threaded stud 16 extending axially therefrom. The threaded stud 16 is of reduced diameter relative to stem 12, thereby defining an abutment shoulder 18 at the lower end of the smooth-walled shaft 12. A portion of stem 12, spaced a relatively short distance above the lower end of said stem, is of slightly reduced diameter as seen at 19, and that portion of the stem has a diametrical bore, or recess, 20 therethrough.

A coupling pin 22 is provided, the said pin 22 being part of a single wire that is shaped to define the pin 22, a connecting shank 24, and a closed loop 26. The loop 26 is of greater inner dimensions than the size of shaft 12 so as to freely fit thereon as shown in the figures.

There is provided an abutment plate, generally indicated at 28, whose edge is hex shaped for convenience in gripping and having flat bearing portions 29 on the under side thereof, and having a central threaded hub 30, which is adapted for threading connection with a ferrule that is generally indicated at 32. The ferrule is exteriorly threaded with a left hand thread and provides a hollow stem, or sleeve means, 34 which defines a smooth-walled central longitudinal bore 36 therethrough. The lower end of sleeve 34 has an outwardly extending flange 38. The sleeve 34 is provided with diametrically disposed openings 40 therein which are adjacent the upper end of the sleeve 34. In the form specifically shown, the openings 40 are elongated axially to open through the upper edge of the sleeve 34.

There is provided an upper rigid washer 42 that slidably surrounds sleeve 34 and which is adapted for bearing engagement with said bearing surfaces 29 of the abutment plate. An elongated, inner, resilient and expandable sleeve 44 is provided surrounding the ferrule 32. An elongated, outer, resilient and expandable sleeve 46 is provided surrounding said inner sleeve 44. A rigid lower washer 50 is provided on ferrule 32 positioned axially between resilient sleeves 44 and 46 and the flange 38, with said washer 50 bearing against flange 38.

A faucet-seat annular cutter disc, indicated at 52, provides one face thereof with relatively coarse cutter teeth 54 and the opposite face thereof with relatively fine cutter teeth 56. The disc is centrally tapped for simple screw connection to stud 16. When the tool 10 is packaged for sale, it is preferably supplied not only with a relatively large cutter disc 52 but also with a smaller cutter disc, shown generally at 52a.

55 In the assembly of the tool 10 for use, the washer 50, the resilient sleeves 44 and 46 and the washer 42, are slidably fitted onto ferrule 32 and then the abutment plate 28 is threaded onto ferrule 32, thereby providing a radially expandable and contractible attaching-and-centering means.

60 The stem 12 is extended through loop 26 and is then slidably extended through bore 36 of the sleeve means 34, and an appropriate cutter disc, 52 or 52a, is threaded onto stud 16 into abutment with shoulder 18. When the shaft 12 is drawn upwardly through sleeve 34 to its uppermost position, as seen in FIGURE 3, then the recess 20 may be selectively aligned with an opening 50 in ferrule 32. In that position the pin 22 may be fitted through the opening 50 and into the recess 20 to a locking position as seen in FIGURE 3, where the stem 12 is locked to ferrule 32, so that rotation of stem 12 effects joint rotation with ferrule 32 relative to the abutment plate 28.

FIGURES 3 to 5 illustrate the manner of use of the

tool 10, and there is illustrated, in each of those figures, a faucet generally indicated at 60 whose gland, or cap nut, has been removed to thereby expose the interior of the upstanding bonnet 62 of the faucet. As shown, the bonnet 62 is provided with exterior threads to which the gland, or cap nut, screw-attaches. The interior periphery of the bonnet 62 may be smooth or may be provided with screw threads depending upon the construction of the particular faucet. The faucet has a lateral extending discharge spout 66, and an interiorly disposed valve seat 68 which lies in a plane perpendicular to the axis of the tubular bonnet 62. The upright axial length of the interior of the bonnet 62 may be shallow and the space between the bonnet 62 and the valve seat 68, as indicated on 70, may also be quite shallow.

In the operation of the tool 10, the expandable attaching-and-centering means portion of the tool is entered into the bonnet 62. The abutment plate 28, or the upper washer 42 abutting plate 28, engages the upper edge of bonnet 62. Then with the plate 28 gripped by one hand, and with pin 22 in position as in FIGURE 3, the shaft 12 is rotated clockwise, or to the right as shown by the arrow, and since the shaft 12 is coupled to the ferrule 32 by means of pin 22, the flange 38 on ferrule 32 is caused to advance axially toward abutment plate 28, thereby exerting forces on the resilient sleeve members 46 and 48 which cause said sleeves to expand radially outwardly and to frictionally engage and grip the inner peripheral surface of the bonnet 62. Since the attaching means engages the cylindrical inner walls of the bonnet 62, this disposes the ferrule 32 concentrically of bonnet 62 and with the longitudinal axis of the elongated sleeve means 34 coaxial of the bonnet and perpendicular to the plane of the valve seat 68.

After the tool 10 has been thus secured to the faucet 60, the pin 22 is withdrawn such as in FIGURE 4, thereby uncoupling shaft 12 from the ferrule 32 and permitting the shaft, or stem 12, to slide axially through ferrule 32 to bring the cutter 52 into cutting engagement with the valve seat 68. Since the shaft 12 is coaxial of sleeve means 34, its axis is squared up perpendicular to the plane of valve seat 68. By pressing down on handle 14 force is transmitted to the cutter 52, and by rotating shaft 12 in the clockwise direction, as indicated by the arrow in FIGURE 4, the cutting and re-seating operation is effected. Teeth 54 are used in a coarse cutting operation, while finishing off may be effected using teeth 56. In order to detach the tool, the shaft 12 is moved upwardly until recess 12 is again aligned with an opening 40, the pin 22 is inserted to re-couple the parts, and then by rotating shaft 12 counter clockwise, the expansion forces on sleeves 46 and 48 are withdrawn, thereby permitting release of tool 10 from faucet 60.

In FIGURES 3 and 4, the tool is shown being used with a faucet 60 having a relatively large bonnet 62, so that the two resilient sleeves 46 and 48 are both used and are positioned concentric of each other to provide for effecting a gripping engagement with the interior periphery of bonnet 62. In FIGURE 5 the tool is shown being used with a faucet 60', wherein the bonnet 62' is of smaller internal dimension than the bonnet shown in FIGURES 3 and 4. With faucet 60' of FIGURE 5, only the inner, or smaller, sleeve 46 is utilized to effect the gripping and centering of the tool in the bonnet 62'.

FIGURES 3 and 4 show the cutter 52 arranged on stem 12 so that the coarse cutter teeth 54 are in position to effect a re-seating operation on valve seat 68. In FIGURE 5 where faucet 60' is smaller, the smaller cutter 52a is shown mounted on the lower end of stem 12. FIGURE 5 further illustrates the use of the fine cutting teeth 56' in effecting a re-seating operation. It will be understood that the cutter to be used is the one of sufficient size to overlie the entire valve seat. The coarse teeth or fine teeth are used depending upon the amount of cutting needed to be performed.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What we claim as new, and desire to secure by Letters Patent of the United States, is:

1. A tool for re-seating a faucet valve seat that is located within a faucet body having a bonnet generally concentric with and spaced from said valve seat, said tool comprising, in combination: selectively radially expandable and contractible, elongated, attaching-and-centering means adapted to be entered into and to grippingly engage the interior periphery of a faucet bonnet, elongated sleeve means carried by said attaching-and-centering means coaxially thereof, an elongated shaft axially slidably and rotatably disposed within said sleeve means and extending axially outwardly of both ends of said sleeve means and of said attaching-and-centering means, said shaft cooperating with the sleeve means to be maintained coaxial of said attaching-and-centering means, a faucet-seat cutter carried on said elongated shaft and spaced axially of and adjacent one end of said attaching-and-centering means, said sleeve means being manipulable to effect selective radial expansion and contraction of said attaching-and-centering means, and coupling means spaced axially of and adjacent the other end of said attaching-and-centering means and including registrable elements on said shaft and said sleeve means and a coupling element cooperating with said elements when registered for selectively coupling the said shaft to the sleeve means to selectively manipulate the sleeve means.

2. A tool for re-seating a faucet valve seat that is located within a faucet body having a bonnet generally concentric with and spaced from said valve seat, said tool comprising, in combination: selectively radially expandable and contractible, elongated, attaching-and-centering means adapted to be entered into and to grippingly engage the interior periphery of a faucet bonnet, elongated sleeve means carried by said attaching-and-centering means coaxially thereof, an elongated shaft axially slidably and rotatably disposed within said sleeve means and extending axially outwardly of both ends of said sleeve means and of said attaching-and-centering means, said shaft cooperating with the sleeve means to be maintained coaxial of said attaching-and-centering means, a faucet-seat cutter carried on said elongated shaft and spaced axially of and adjacent one end of said attaching-and-centering means, said sleeve means being manipulable to effect selective radial expansion and contraction of said attaching-and-centering means, said sleeve means defining a radial opening therein spaced axially of and adjacent the other end of the said attaching-and-centering means, said shaft having a recess therein that is adapted to be selectively aligned with said radial opening in the sleeve means, and a pin selectively insertable into said recess in the shaft and protruding through said radial opening in the sleeve means for coupling the sleeve means to the shaft for selective joint rotation.

3. A device as set forth in claim 2 wherein said pin is connected to an enlarged loop that loosely surrounds the shaft to permit manipulation of the pin while preventing misplacing of the pin.

4. A device as set forth in claim 2 wherein said recess in the shaft is spaced from the cutter such that when the said recess is aligned with the radial opening in the sleeve means the cutter is positioned axially closely adjacent the sleeve means.

5. A device as set forth in claim 2 wherein said attaching-and-centering means includes an exteriorly threaded elongated ferrule with an outwardly extending flange at one end thereof, elongated elastic sleeve means concentric with said ferrule between the ends thereof, annular

abutment plate means threaded to the ferrule and providing for relative axial movement of the ferrule flange toward and away from said plate means, said plate means being of a dimension greater than the interior dimension of a faucet bonnet, so that said plate means are adapted to overlie and engage at least a portion of a faucet bonnet to which the device is to attach.

6. A device as set forth in claim 2 wherein said attaching-and-centering means includes an exteriorly threaded elongated ferrule with an outwardly extending flange at one end thereof, elongated elastic sleeve means on said ferrule between the ends thereof, annular abutment plate means threaded to the ferrule and providing for relative axial movement of the ferrule flange toward and away from said plate means, said plate means being of a dimension greater than the interior dimension of a faucet bonnet,

so that said plate means are adapted to overlie and engage at least a portion of a faucet bonnet, and bearing washers on said ferrule engaging both ends of said elastic sleeve means and disposed between said elastic sleeve means and both said ferrule flange and said plate means.
